JOSEPH M. MERROW, OF HARTFORD, CONNECTICUT, ASSIGNOR TO THE MERROW MACHINE COMPANY, OF HARTFORD, CONNECTICUT, A CORPORATION OF CONNECTICUT.

THREAD-CONTROLLING DEVICE FOR SEWING-MACHINES.

1,173,296.

Specification of Letters Patent.

Patented Feb. 29, 1916.

Application filed August 16, 1911. Serial No. 644,346.

To all whom it may concern:

Be it known that I, JOSEPH M. MERROW, a citizen of the United States, residing in the city of Hartford, county of Hartford, and 5 State of Connecticut, have invented certain new and useful Improvements in Thread-Controlling Devices for Sewing-Machines, of which the following is a full, clear, and exact description, reference being had to 10 the accompanying drawings, forming a part of the specification, and to the reference-numbers marked on the said drawings.

This invention has for its object to provide a thread controller for taking up and 15 pulling off the thread and controlling the slack thereof, and is shown and described as connected with the needle mechanism and acting upon the needle thread in a three thread overseaming machine of the well 20 known Merrow type, the general construction of which is described and referred to in Patent No. 734,987, issued July 28th, 1903, to William H. Stedman.

The invention consists in thread controlling 25 devices and in the construction, relation and application thereof as described and claimed.

In the drawings: Figure 1 is an end elevation, showing the thread controlling devices and partially illustrating the overseaming machine. Fig. 2 is a front elevation of the needle mechanism and of the thread controlling devices and also shows in dotted lines adjacent portions of the machine. Figs. 3, 4 and 5, constitute a series of 35 views illustrating the needle and thread controller in end elevation, apart from the machine, and show several steps in the control of the needle thread.

40 Throughout the several figures of the drawings like reference numbers denote the same parts.

The reference numeral 1 indicates the machine frame, 2 the head, 3 the needle plate, 45 4 the oscillating needle carrier, 5 the pivotal stud for the carrier, 6 the needle clamp and 7 the eye pointed curved needle. The oscillatory reciprocation of the needle is attained by means of the usual mechanism intermediate the upper main shaft 8 and the needle carrier 4 the shaft having at its end a 50 enlarged head that is provided with a wrist pin 10 which latter forms a pivotal connection with one end of a link 11 while

the opposite end of the link similarly engages a pin 12 on the needle carrier 4.

The numbers 13 and 14 denote loopers which coöperate with each other and with the needle in making a stitch. The number 15 denotes a well known type of thread tension and 16 a fixed thread guide.

The thread controller, denoted as a whole by the number 17, is arranged to operate between the needle 7 and the disks 15 of a thread tension which latter is shown as 65 supported on the machine head 2. The fixed thread guide 16 is also usually provided but is not used when the thread tension can be easily located suitably to hold the thread in proper relation to the controller as the tension devices then act as a thread guide. The link 11 is in the machine illustrated utilized as a carrier for the thread controller 17, the latter being secured to the link by the screw 18. The thread controller extends rearwardly and upwardly from the link 11 and near its free end there is a thread eye 19 while the extreme end portion 20 of the controller is formed as a thread engaging horn that is turned laterally slightly, as 70 shown in Fig. 2. The needle thread 21 passes between the tension disks 15 and then in turn through the eye of the thread guide 16, the eye 19 of the controller 17 and to and through the eye of the needle 7. The eye 19 of the 75 thread controller 17 travels in a continuous curvilinear path and the horn or point 20 travels in a path similar to that of the eye 19 but of a somewhat more amplified orbit, the said eye 19 and horn 20 (which constitute the thread engaging elements of the controller 17) each making a complete 80 traverse of its orbit with each complete reciprocation of the needle 7.

In operation and commencing with the 95 needle at or near its highest position and with the controller nearly in a vertical position, practically as shown in Fig. 1: As the shaft 8 is turned in the direction of the arrows adjacent the shaft end 9, the needle 7 100 travels downward toward the needle plate 3, the controller 17 moves backward toward the position shown in Fig. 3 and holds the needle thread taut to take up all unnecessary slack in the thread and if needed draws out thread through the tension devices. Continued turning of the shaft 8 causes the needle to be carried to its lowest position 105

while the thread controller is moving upward and swinging forward to about the position shown in Fig. 4. During this part of the movement of the controller the needle 5 has been moving downward, rapidly at first and toward the end of its throw very slowly and the combined action of the eye 19 and horn 20 of the controller lets out or loosens up the thread at about the same rate that the 10 needle draws the thread downward so there is little or no slack thread between the controller and the needle. While the needle is traveling slowly or is at rest at its lowest position, the controller is moving relatively 15 rapidly and the action of the eye 19 alone (if the horn 20 were removed) would be to slacken the thread materially, but the forward edge of the horn engages the thread in season to practically compensate for or 20 counteract any objectionable slackening effect of the movement of the eye of the controller and keeps the needle thread suitably taut and in some cases draws a slight amount of thread through the tension devices. The 25 slack is kept out of the thread by the controller as it travels downwardly and rearwardly into about the position shown in Fig. 5, when the backward movement of the controller begins and the thread eye of the controller begins to tighten the thread faster 30 than the forward edge of the horn releases it, thereby setting the stitch and drawing nearly enough thread through the tension disks to form the next stitch and the horn 20 35 becomes temporarily disengaged from the thread as shown in Fig. 3. The end of the horn is turned or offset slightly toward the thread to insure its engagement therewith and the rear edge of the said horn is made 40 smooth and with a convex surface so that if the needle thread is loose or accidentally left in the rear of the point of the horn, as illustrated for instance in dotted lines in Fig. 5, the point of the horn will push the thread 45 laterally and the thread will slide around the end of the horn to the front side thereof by the time the thread controller has moved into about the position shown in the Fig. 3, and thereafter the thread will remain 50 in front of the horn.

As already mentioned, one of the thread engaging elements of the controller moves in an orbit of greater amplitude than the other, and therefore, the angular position 55 of the two elements with relation to a line between the thread guide and the needle varies in such manner that a double bend is developed in the thread during a portion of each excursion of the controller, whereby a 60 greater slack may be compensated for and the thread pulled off to better advantage than with the use of a single thread engaging element.

The opening in the controller for the 65 passage of the thread is shown and described as

an eye which is the preferred form for most cases, although only one side of the eye is active and the opposite side might be omitted. In practice it has sometimes been found advantageous to so construct the controller 70 in order that the thread may be passed into a recess instead of being threaded through an eye.

It will be observed that the form of the front edge of the controller horn and its position or distance from the eye of the controller, as well as the amplitude of motion of the controller and the relative location of the thread guide affect the length of the thread taken up or let out as well as the 80 times of such actions relative to the operations of the needle.

Having thus described my invention, I claim:

1. In combination, in a sewing machine, 85 a fixed thread guide, a thread controller having a passage for continuous engagement of the thread, a thread engaging horn integral with the controller and means for operating the controller whereby in a cycle 90 of its motion the horn is caused to engage the thread between the said thread passage and the fixed thread guide and also to become disengaged from the thread.

2. In an overseaming machine, in combination with the stitch forming mechanism and thread guiding means thereof, a moving thread controlling implement having a thread passage near the extremity of the free end thereof and a coöperating thread 100 engaging horn at the extremity of the said implement, the said horn inclining at an angle to the direction of length of the portion of the said thread controlling implement through which the thread passage passes, 105 and means for carrying and actuating the controller whereby the horn is alternately moved into and out of engagement with the thread, substantially as and for the purposes described. 110

3. In an overseaming sewing machine and in combination: a stationary thread guide, a needle carrier and a thread controlling implement operating on the thread between the said thread guide and needle 115 carrier, the said implement being provided with a thread carrying eye and a tapering horn, the said eye and horn each traveling in a continuous ovate path, the orbit of movement of the tapering portion of the 120 horn being of greater peripheral length than the orbit of movement of the eye, and eccentric thereto; whereby the horn may be carried into and out of engagement with the thread upon which the eye is operating, 125 substantially as and for the purposes herein shown and described.

4. In a sewing machine: stitch forming mechanism embodying a needle, a needle carrier pivoted on a fixed center, a driving 130

crank and a link connecting the driving crank and the needle carrier; a thread controller projecting from the link and having two thread engaging elements around which the thread is caused to intermittently make a double bend.

5. In a sewing machine; a thread guide, a thread controlling implement having two thread engaging elements located thereon and at the same side of the controller's support, a carrier supporting the controller and means for actuating the carrier whereby one of the said elements is carried into and out of engagement with the thread between the other element and the thread guide at each cycle of the controller's travel.

6. In an overseaming sewing machine; a thread controlling implement, a carrier supporting the implement, two thread engaging elements on the implement located thereon at the same side of the point of the implement's support but at different distances from said support, whereby one of the said elements may operate upon the thread to form a second bend beyond the point of operation of the other element, and means for actuating the carrier whereby the thread engaging elements of the implement are caused to travel in eccentric paths of different amplitude and of ovate form.

7. In a sewing machine, a thread controlling device including an implement having an element constituting a point of constant

thread engagement and an element intermittently free from and around which a single coil of thread is developed during its operative movements, each element at intervals taking up the slack occasioned by the relief of the thread by the other element and means for supporting and actuating the implement.

8. The combination with a sewing machine having stitch-forming mechanism, thread guiding means and tension means, of a thread controller including in a single implement, a thread controlling element co-operating with a slack compensating element to pull off and control the thread, said elements being relatively fixed and one of said elements moving alternately into and out of engagement with the thread.

9. In a sewing machine and in combination with a tension, a fixed thread guide and an eye pointed needle; a thread controlling device provided with positive actuating means, and having, in a single moving implement, a constantly operative thread passage and an intermittently operative horn portion, co-operating with each other to alternately produce a single coil and a single bend in the thread.

JOSEPH M. MERROW.
